J. M. CALDERÓN, JR

COLLAPSIBLE BOAT

Filed March 20, 1925

UNITED STATES PATENT OFFICE.

JOSÉ MARÍA CALDERÓN, JR., OF RIO GRANDE, PORTO RICO.

COLLAPSIBLE BOAT.

Application filed March 20, 1925. Serial No. 16,907.

To all whom it may concern:

Be it known that I, JOSÉ MARÍA CALDERÓN, Jr., a citizen of the United States, residing at Rio Grande, in the county of Humacao, Porto Rico, have invented certain new and useful Improvements in Collapsible Boats, of which the following is a specification.

This invention relates to a collapsible or knock-down-boat, the invention being intended more particularly for embodiment in a small skiff or canoe, so that the same can be readily transported by the user, the invention having for an object the provision of a novel and simple type of collapsible boat.

For further comprehension of the invention, and of the objects and advantages thereof, reference will be had to the following description and accompanying drawing, and to the appended claims in which the various novel features of the invention are more particularly set forth.

Fig. 1 of the drawing is a plan view of my improved collapsible boat.

Fig. 2 is a side view thereof.

Fig. 3 is a transverse sectional view taken on the line 3—3 of Figure 1.

Fig. 4 is a detail transverse sectional view through one of the gunwales, this view being taken generally on the line 4—4 of Figure 5.

Fig. 5 is a detail side elevational view of the parts shown in Figure 4.

Fig. 6 is an edge view of the seat, showing the same folded.

Fig. 7 is a longitudinal sectional view of the floor of the boat, showing the said floor as folded.

Fig. 8 is a detail plan view showing the construction of the gunwale of the boat.

Fig. 9 is a face view showing the collapsible car or paddle used with the boat.

Fig. 10 is a similar view to Fig. 4 but showing a modified construction.

As here embodied my improved boat comprises a collapsible frame consisting of the lower side members 10 and the upper side members 11. These side members are parallel throughout their main lengths, the lower members 10 being spaced apart a less distance than the top members 11. At their front and rear ends these side members converge toward one another, and connect to the opposite ends of the inclined bow and stern posts 12 and 13. These side members are constructed as indicated in Fig. 8 of the

drawing, each comprising a series of tubes 14 having set in one end the studs or plugs 15 that engage removably in the end of the adjacent tubes and are fixed therein by set screws 27 to be presently referred to. These top and bottom side members have sockets such as 20 entered thereinto from the lower and upper sides thereof respectively, which receive the diminished ends of the ribs 21 of the boat, these ribs being also of tubular construction.

The sheathing of the boat is shown at 23 and is formed of canvas or other waterproof fabric which is constructed to fit snugly upon the frame just described, at its upper edge this sheathing may be wrapped or turned inward over the gunwale members 11, as clearly shown in Fig. 4 of the drawing. I preferably provide also a narrow decking that extends along the sides of the boat. This decking is made up or comprised of a strip 24 of like material to the sheathing 23 that is fitted over the top of the latter as shown in Fig. 4, the two parts 23 and 24 having registering eyelets such as 26 of generally elliptical form, through which are passed the fastening screws 27 that hold the said parts in place, certain of these screws being arranged to bear on the tops of the ribs 21 and act to retain the latter fixed to the members 11, as well as secure the sheathing and decking elements to the said members 11.

To constitute a flooring for my improved collapsible boat, I provide a series of boards 30 that are of a length equal to the distance between the remote sides of the lower side members 10 and which are arranged transversely of the boat with their ends resting on the said members 10. These boards are preferably all linked together by means of the rings 31 that are passed through apertures 32 in the edge portions of the boards. This method of joining the flooring boards to one another permits of the same being folded one upon the other into a compact bundle as indicated in Fig. 7 of the drawing.

The seat for my improved boat is made up of two sections these sections comprising short boards 35 that are hinged to one another at adjacent ends, or midway between opposite ends of the seat. Hinged to the ends of the seat are hooks 36 that are caught around the gunwale members 11 and support the seat. To prevent the two halves of the seat from collapsing on one another

when the seat is in use a bar 37 may be pivotally connected at one end to one section of the seat as at 38 to swing parallel to the seat and engage under a cleat 39 arranged obliquely on the other section of the seat. The seat when not in use may be folded as indicated in Fig. 6 of the drawing. Suitable oars or paddles such as that shown in Fig. 9 are provided, these oars or paddles each consisting of a blade 42 and a number of detachable handle sections 43.

In the construction shown in Fig. 10 of the drawing the sheathing 23 is carried downward inside the gunwale as at 23' and is formed with a number of eyes such as 45 through which are passed fastening arms such as 46' turned backward to lie along the ribs and engaged within collars such as 48 slidably along said ribs to retain them in position. This construction enables the sheathing to be readily stretched over the frame, and the use of the set screws may be dispensed with to hold the ribs engaged with the top and bottom side members since the sheathing, when stretched, acts in this manner.

My improved collapsible boat may be readily taken apart and assembled, and when in collapsed position may be readily inserted in a bag for transportation.

Having thus described my invention what I claim as new and desire to protect by Letters Patent of the United States is as follows:—

35 1. A collapsible boat comprising a frame made up of top and bottom side members each consisting of a number of sections detachably secured to one another, ribs extending between the upper and lower side members and detachably secured to the same, and a flexible sheathing element detachably secured on said frame, and a flexible decking element separate from said sheathing element secured upon said frame.

40 2. A collapsible boat comprising a frame made up of top and bottom side members each consisting of a number of sections detachably secured to one another, ribs extending between the upper and lower side members and detachably secured to the same, and

a flexible sheathing element detachably secured on said frame, and a flexible decking element separate from said sheathing element, said flexible decking element overlapping the top edge of 55 said sheathing element, said two elements being formed with registering eyelets, and screws passed through said eyelets to secure the said elements to the said frame.

3. A collapsible boat comprising a frame 60 made up of top and bottom side members each consisting of a number of sections detachably secured to one another, ribs extending between the upper and lower side members and detachably secured to the same, and a flexible sheathing element detachably secured on said frame, and a collapsible flooring for said boat, said flooring being made up of a number of transversely extending boards having apertures at their edges, and 65 rings passed through the said apertures to connect the said boards together.

4. A collapsible boat comprising a frame made up of top and bottom side members each consisting of a number of sections 75 detachably secured to one another, ribs extending between the upper and lower side members and detachably secured to the same, and a flexible sheathing element detachably secured on said frame, and a collapsible 80 flooring for said boat, and a seat freely suspended from the said top side members and consisting of two halves hinged to one another.

5. A collapsible boat comprising a frame 85 made up of top and bottom side members each consisting of a number of sections detachably secured to one another, ribs extending between the upper and lower side members and detachably secured to the same, 90 and a flexible sheathing detachably secured on said frame, and means for stretching said sheathing element on said frame, comprising arms hinged to the said ribs and adapted to be passed through eyes in the edge of said 95 sheathing element.

In testimony whereof I have affixed my signature.

JOSE MARIA CALDERON, JR.
